CLAIM

The ornamental design for a wrist-wearable time teaching instrument, substantially as shown and described.

DESCRIPTION

FIG. 1 is a top plan view of a wrist-wearable time teaching instrument showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a bottom plan view thereof.
